UNITED STATES PATENT OFFICE.

FRANK BURJANEK, OF CHICAGO, ILLINOIS, ASSIGNOR TO HERHOLD CHAIR CO., OF CHICAGO, ILLINOIS, A CORPORATION OF ILLINOIS.

CHAIR.

1,253,346.

Specification of Letters Patent.

Patented Jan. 15, 1918.

Application filed September 28, 1914. Serial No. 863,949.

To all whom it may concern:

Be it known that I, FRANK BURJANEK, a citizen of the United States, residing at Chicago, in the county of Cook and State 5 of Illinois, have invented certain new and useful Improvements in Chairs, of which the following is a description.

My invention belongs to that general 10 class of devices known as chairs, and relates particularly to that style of chairs known as bent wood chairs. While I have referred to it as a bent wood chair, the invention may be embodied in other styles of 15 chairs, as will be obvious from the description. The invention has among its objects the production of a chair that is attractive, durable, efficient and satisfactory. A chair constructed in accordance with the invention described herein is extremely rigid, 20 the legs and back being braced and secured in place in a substantial and yet at the same time attractive manner.

To this end my invention consists in the 25 novel construction, arrangement and combination of parts herein shown and described, and more particularly pointed out in the claims.

In the drawings, wherein like reference 30 characters indicate like or corresponding parts,

Figure 1 is a perspective view of a chair embodying my invention;

Fig. 2 is a cross sectional view through the seat and lower part of the chair, taken 35 substantially on line 2, 2 of Fig. 1;

Fig. 3 is a sectional view, taken substantially on line 3, 3 of Fig. 4;

Fig. 4 is a sectional view, taken substantially on line 4, 4 of Fig. 3.

Referring to the drawings, 1, 1 represent 40 the front legs of the chair, and 2, 2 the rear legs. Secured to the legs is a suitable seat 3 of veneer, cane, or the equivalent, which is preferably carried by a frame or ring 5.

As shown, the rear legs are preferably 45 extended upwardly and looped to form a back 4. The rear legs 2 are preferably secured to the exterior edge of the ring or frame 5 in any of the well known manners, screws 50 7 being shown for the purpose. The front legs are set in sockets in the ring or frame 5 and suitably secured thereto. As shown, the upper ends of the legs 1 are each shouldered, as at 9, and the extended end 8 fitted 55 into sockets 5' in the ring 5. The legs may

be secured in place in the manner hereafter described.

Arranged below the seat 3 and secured to the legs 1 and 2 are crossed bracing members 10. The members 10 each have one end 60 secured to a rear leg 2 intermediate the seat and end of the leg, as shown in Fig. 2, the same being suitably secured in place by screws 14, or their equivalent. The opposite end of each is preferably extended, as 65 shown, and secured to the ring or seat frame 5, and to the end 8 of the leg 1 by a screw 11, or its equivalent. The same is also preferably secured to the front legs 1 by screws 12, or the equivalent, as most clearly shown 70 in Fig. 2. As shown in Fig. 3, the end of each bracing member 10 is preferably provided with a shoulder 13 adapted to underlie the ring 5 and formed to fit close to the leg 1, as is most clearly shown in Fig. 4. 75 The braces are preferably secured together by screws or bolts 15 at their crossing, as shown in Fig. 2.

The seat 3 may be secured to the seat frame 5 in any suitable manner, the frame 5 80 being preferably recessed or countersunk, as at 6, upon which the seat may rest. The method of securing the seat in place described depends upon the style of seating employed, whether it be cane, veneer, leather, 85 fiber, or the equivalent. The parts may be glued together, as well as secured by screws, if so desired. By this construction the legs are securely fastened together and at the same time substantially braced. It will be 90 seen in the construction described that the seat and legs constituting the chair are securely braced and reinforced by a brace member extending from one leg intermediate the end and the seat to an alternate leg 95 at the seat, which brace member is in itself strengthened and made rigid by a similarly formed brace member connecting the remaining legs. By constructing the braces as shown the front edge of the chair is securely 100 braced and connected with the rear legs, so that not only are the front parts secured together and braced, but the rear legs are similarly braced from the front side.

Owing to the method of securing the 105 members 10 to the front leg and frame 5, the front legs are prevented from pulling out or working loose. An additional back member may be employed, if desired, a loop member 110 being shown in Fig. 1. It is, of course,

obvious that the parts may be bent or sawed in different shapes than those shown, with the same result.

Having thus described my invention, it is 5 obvious that various immaterial modifications may be made in the same without departing from the spirit of my invention; hence I do not wish to be understood as 10 limiting myself to the exact form, construction, arrangement or combination of parts herein shown and described, or uses mentioned.

What I claim as new and desire to secure by Letters Patent is:—

- 15 1. In a chair of the kind described and in combination, a seat including a seat frame having recesses at the front side, a pair of rear legs suitably secured to the said seat frame, a pair of front legs having their upper ends positioned in said recesses, and formed with a shoulder overlying the under side of the frame, a bent brace secured to each rear leg intermediate the ends thereof, and extended across the chair below the seat 25 to adjacent the upper end of one of the front legs, with a portion adjacent the leg cut away at the seat frame, and means for securing said brace and leg to the seat frame, with a portion of the frame between the same.
- 30 2. In a chair of the kind described, the combination of a plurality of legs, a seat carried thereby, said seat including a suitable frame, the front pair of legs having their upper ends recessed in said seat frame, and 35 cross brace members secured to the rear legs and bent at the other ends to adjacent the upper ends of said front legs, said braces formed to closely fit the front legs adjacent the upper ends thereof, with a portion cut 40 away to clear a portion of the inner side of said frame, and fastening members extending through said braces, said seat frame and said front legs, said fastening members being of sufficient length to engage the seat 45 frame on the outer side of said legs, but not to project entirely through the frame.
- 50 3. A leg fastening for chairs comprising a chair seat frame having a socket therein,

a leg having its upper part disposed within said socket, a brace, the upper portion of 50 which extends along one side of the wall of the socket and being formed to contact with a substantial portion of the leg below the socket, and fastening means extending through the brace, the chair frame and the 55 leg, substantially as described.

4. A leg fastening for chairs comprising a seat frame having a socket therein, a leg reduced in diameter at one end and fitting 60 in the socket, a brace having its upper end extending along one side of the wall of the socket in the chair frame and also being formed to fit the contour in a substantial portion of the leg below the socket, and fastening means extending through the brace, 65 the chair frame and leg, substantially as described.

5. A leg fastening for chairs comprising a seat frame having a socket therein, a leg reduced in diameter at one end and fitting 70 in the socket, a brace having its upper end extending along one side of the wall of the socket in the chair frame and also being formed to fit the contour in a substantial portion of the leg below the socket, and 75 fastening means extending through the brace, chair frame and leg, and an additional fastening device passing through the brace and engaging the leg at a point well below the chair frame.

80 6. A leg fastening for chairs comprising a seat frame having a socket therein, a leg fitting within the socket, a brace having a portion extending adjacent the leg, and a single fastening means extending through 85 the brace, the chair frame and the upper portion of the leg, substantially as described.

In testimony whereof, I have hereunto signed my name in the presence of two sub- 90 scribing witnesses.

FRANK BURJANEK.
